TEMPLE FOR A SPECTACLE FRAME

Richard R. Maiese, Webster, and Harold F. Whiting,
Attleboro, Mass., assignors to American Optical Cor-
poration, Southbridge, Mass.

Filed Mar. 25, 1970, Ser. No. 22,049

Term of patent 7 years

Int. Cl. D16—08

U.S. Cl. D57—1

FIG. 1

FIG. 2

FIG. 1 is an elevational view of a temple for a spectacle frame showing our new design; and

FIG. 2 is an enlarged fragmentary view of a part of the temple shown in FIG. 1.

The opposite side of the temple is substantially flat and unornamented.

I claim:

The ornamental design for a temple for a spectacle frame, as shown and described.
